(54) **BRICK, MOULDING**

(76) Inventor: **Ezra (Fish) or Fisk**

Ezra Fish and Benjamin in, Hinske.

WITNESSED, &c., signed to in these letters patent, as making part of the same, containing a description on the words of the said Ezra Fish & Benjamin in Clark, by themselves or their improvement on the machine for mauling ticks, &c.,

The machine consists of a grinder & a mauler, which are connected in their construction & operation. The grinder is a square box, which is forty inches square inside, & three feet deep. Four posts of timber that are seven inches square, are connected in the corners of the box extending three feet below, so that four legs to support the grinder. These legs are connected by suitable girders; on two opposite sides, the girders are inverted at the bottom of the box to support the floor of the grinder. On the other sides, the girders are inserted eight inches below the floor girders. The floor girders are also connected in the middle, by a girder, that aids in supporting the floor. The box is lined from the top downward, contracting the size of the box six inches each way, leaving a space of one foot unlined in the lower part of the box.

A vertical shaft works in the center of the box. This shaft, which is five feet long, & eight inches diameter, is secured by a suitable binder that passes across the top of the box. The lower end of the shaft passes through a circular aperture in the floor and an iron gudgeon in the end of the shaft works in the grinder beneath. The circumference of the shaft is divided into eighths by parallel lines drawn at the points of eighths from the lower end upward to the top of the box. Lines are also drawn spirally round the shaft, so as to leave a space of four inches between them. Perforations are made of a suitable size, say one & a half inch, at all points where the lines intersect each other, & knives are inserted in all their perforations.

The knives that work in the upper part of the box are narrow, but those that work in the lower part of the box are pressure-knives being eight in. number, 4' eight inches wide at the outward ends, but taper down to three inches in width at the shaft, extending outward till they come nearly in contact with the insides of the box. The pressure-knives lay in an inclined position, the edges rising above the backs in an angle of about forty degrees, & the backs which are two inches thick rise one inch from the floor.

The moulds consist of a receiver, which is an oval box that receives the mortar as it is pressed from the grinder; two air apertures in the lower part of the grinder box; and a conductor, which is a sort of grating, the air apertures of which the mortar passes into the brick moulds. The receiver is six inches deep, the width corresponding to the length of the brick; length of it corresponding to the length of the flaskel of brick. It should, on one side of the receiver, be an opening four inches deep, extending the whole length of the box, & leaving a bar above & below the opening, which bars serve to connect the ends of the box on that side. The apertures in the conductor correspond in form, size & number to the moulds in the flaskel to be used, but the partitions between the apertures in the grating are one inch thicker at one end shorter than the partitions between the brick moulds.

The side pieces of the grating, & also the bars are excavated. The excavations are filled with sponge to the whole covered with coarse strong woollen cloth, the upper & lower edges of the cloth being confined to the wood by tacks. It is small enough sufficient to contain one gallon, is placed in front of the grating for the purpose of supplying the sponge with water, which is conveyed in small tubes from the sink, this corresponding, perforations made in the front

pieces of the grating. - The pressure of the mortar as it passes thro' the grating causes the mortar to ooze out thro' the 'holes,' which facilitates the discharge of the bricks from the moulds.

The grating may be used with or without the receiver according as the clay shall require. - To connect the moulds with the grinder, the conductor is attached to one side, or it may be attached to two opposite sides of the grinder, resting upon arms which extend outward from the posts of the grinder. - The grating is so stationed that the upper side of it falls inwards a half below the upper side of the floor of the grinder. The receiver sits upon the grating, the open side coming in close contact with the side of the grinder, the opening in the side of the receiver corresponding exactly to a like opening made in the side of the grinder at the bottom. The grating is secured in its place by iron bolts that pass thro' the four pieces of the arms on which it rests. The receiver is confined in its place by a tie at the ends which connects it to the grating. To work the moulds they are placed on a slide that works horizontally under the grating.

This slide is a square frame not about thirty inches long to twenty inches wide. A floor, fifteen inches wide, is placed upon that end of the slide which works under the machine, the upper side of the floor forming a level with the upper side of the moulds as they lay on the slide. The slide works on two bed pieces that are confined in the lower joints of the grinder. On the upper sides of those bed pieces are tongues of sufficient length to accommodate the motion of the slide, so these tongues work in corresponding grooves in the under sides of the cross pieces of the slide. The slide is worked by a wheel that is fifteen inches diameter, placed in a vertical position under the middle of the slide, the shaft of the wheel being supported by arms that extend

from the legs of the grinder. This wheel is wrapped by a chain, the ends of which pass crosswise from the top of the wheel to the crosspieces of the slide where they are confined. The wheel is moved by means of a lever of about forty inches long, attached to the end of the shaft. It forces the mortar from the receiver. On the grating a follower is mounted in the manner. The follower is suspended from the top pieces of a square framework that stands in a vertical position in front of the grinder and encompasses the grinder's appendages. The follower is forced downward by a foot pressing on a lever that works horizontally in the lower part of the machine. This lever is suspended from the midline of the bottom pieces of the above mentioned framework, by a link, one end of this lever being attached to a leg of the grinder, the other end extending outward on the right or left of the workman at his elevation. The follower is raised by two chains which pass over pulleys that are suspended from the arms of the grinder, one end of the chains being fastened to the bottom pieces of the frame work, & the other end fastened to the shaft of the wheel. So when as the follower moves easily from the mortar, in its motion of rising, it is permitted to rise in two or three places, and on the under side. Mortar & water are so distributed as to cover those perforations. To operate this machine, a horse is attached to a suitable sweep that is fixed on the top of the grinder's shaft. A sufficient quantity of mortar must be enough to fill the grinder. The slide being withdrawn to the follower raised, the puddle of mortar in the grinder immediately fills the ~~receiver~~, the workman places a flat-plate on the slide, or by the elevation of the hand lever, the mortars are carried under the grating. The workman having his foot upon the foot lever, by a sudden sudden pull the lever inwards, the hand lever being brought to its first position.

the slide is withdrawn, the follower, in the same direction, is raised, so the mortar, by air, forces into the moulds. The workman removes the flasks of moulds already filled, & places another on the slide. The operation is repeated. After first filling the grinder, if the clay is of a fine soft texture, it may be used in a crude state. But if the clay is of a coarse, hard texture, it must be about half wrought, or broken, before it is cast into the machine.

The inventors of this machine do not claim to have discovered any improvement in the grinder, so far as its operation converts clay into mortar suitable for making bricks; but they do claim to have discovered an improvement in the grinder, so far as its principles & construction, operation, &c, &c, to supply a machine for moulding bricks with mortar after it is wrought.

But they further claim to have discovered a method of combining & applying the principles & features which comprise this machine, so as to produce a new effect.

No moulds like in the machine above specified, so as to realize the necessary, except in the quantity of the moulds, they must agree in form & size.
